UNITED STATES PATENT OFFICE.

SAMUEL HUMMERSON, OF CLAY TOWNSHIP, CARROLL COUNTY, INDIANA.

GAME APPARATUS.

Application filed September 30, 1926. Serial No. 138,752.

This invention relates to amusement games requiring the exercise of skill and judgment on the part of players to successfully operate the apparatus, the invention having 5 reference more particularly to overturning figures that must be overturned by being struck by balls thrown by players.

An object of the invention is to provide an improved amusement game device that 10 shall be so constructed as to definitely indicate the skill of the player and different degrees of skill.

Another object is to provide an improved amusement game apparatus of simple construction which will be attractive to visitors of amusement places and permit of operation without requiring much time in studying the mode of operation, which apparatus shall be adapted to be readily transported 20 from place to place and set up for use, and which shall be durable and economical in use.

With the above-mentioned and other objects in view, the invention consists principally in an overturning figure of such construction as to be adapted to remain upside down as a result of skillful ball throwing, the invention consisting further in the parts and combinations and arrangements 30 of parts as hereinafter particularly described and claimed.

Referring to the drawings,—Figure 1 is a front view of the improved game apparatus; Fig. 2 is a vertical sectional view approximately central, and Fig. 3 is a side view 35 partially in section.

Similar reference characters in the different figures of the drawings indicate corresponding elements or features of construction herein referred to in detail.

A practical embodiment of the invention comprises a suitable stand or frame which may be adapted to support any suitable number of figures, one figure being sufficient to 45 illustrate and describe the invention. As shown the stand comprises a suitable base 1 which may be suitably secured in place by any suitable means, two standards 2 and 3 being secured to the base, preferably 50 so as to be inclined forwardly. An axle shaft 4 is inserted through suitable holes in the upper portion of the standards with separated thimbles 5 and 5' on the shaft and nuts 6 and 6' on the ends of the shaft to 55 secure it to the standards.

A figure holder is provided which is of novel construction and comprises an arm member which may be composed of wood and having a main part 7 and a relatively shorter back part 8 secured to the main part by means of a bolt 9, the main part having a beveled upper rear face 10 and a relatively narrow normally lower end 11 in which is a bolt 12 that is connected to one end portion of the back part with a separating 60 thimble 13 on the bolt between the parts, the part 8 preferably having a relatively thin portion 14 to which the bolt is directly connected. The rearward side of the main part 15 preferably is cut away a suitable distance from the end 11 so that a slot 15 is provided in the holder with a journal bearing 16 at the end of the cut away portion or inner end of the slot, or the slot may be otherwise formed in the holder, the journal bearing being located at a suitable distance from either 70 end of the holder. The bolt 12 and thimble 75 constitutes the outer end of the slot and may be removed when connecting the holder to the shaft. The construction is such that the bearing 16 is directly supported on the shaft between the thimbles thereon and is suitably balanced so as to stand in approximately vertical position when not disturbed, 80 with the slot beneath the shaft.

The holder supports and carries a suitable figure on the front of its normally upper portion, preferably on a suitable figure plate secured to the holder and having any desired figure painted on its face, such as a 85 grotesque representation of an animal having a body portion 17 mainly arranged higher than the shaft and the foot portion 18 somewhat lower than the shaft, the body portion having a head portion 19 thereon which is located forward of the beveled back 90 10. Preferably the holder is approximately balanced by providing the back part 8 with a relatively large lower portion 20 affording 95 considerable weight. Preferably the shaft has washers 21 thereon at opposite sides of the figure plate holder.

In practical use the player uses balls, 100 which may be of the character of base balls, and they are thrown at their head portion 105 of the figure with the purpose of throwing the ball with sufficient force to overturn the figure until the holder slides down and hangs on the shaft 4 upside down, as in Fig. 3, indicating higher skill and force in throw- 110

ing the ball. In some cases the figure may be struck with less force or on its body portion and cause mere rocking motion, usually 5 amusing to bystanders, clearly indicating a lesser degree of skill and force in throwing the ball. After each figure is overturned an attendant turns it back to normal position in which it remains until overturned as before in the practice of the game.

10 What is claimed as new is:

1. A game apparatus including a horizontal shaft, means to support the shaft, and a figure plate provided with a holder having a shifting pivotal connection with the shaft 15 permitting overturning and vertical shifting of the holder.

2. A game apparatus including a supporting stand, a shaft horizontally secured to the stand, and a figure plate provided with a 20 holder supported on the shaft to rock thereon, the holder having a longitudinal slot normally beneath the shaft permitting the holder to overturn and slide downward invertedly.

25 3. A game apparatus including a supporting stand, a shaft horizontally secured to the stand, a figure plate holder having a journal bearing rotatably supported on the shaft and a slot permitting the holder to overturn and slide across the shaft and 30 downward into relatively inverted position, and a figure plate secured to the front of the holder.

35 4. A game apparatus comprising a base,

standards secured in forwardly inclined position to the base, an axle shaft horizontally secured to the upper portions of the standards, a figure plate holder having a journal bearing in proximity to the longitudinal center of the holder and a slot on one side of 40 said bearing through which said shaft extends, the holder normally being pivotally supported uprightly by said bearing on the shaft and permitted to be overturned to hang upside down on the shaft, and a figure carried on the normally upper forward portion of the holder.

45 5. In a game apparatus, the combination with a horizontally supported axle shaft, of a figure holder comprising a main part and a back part arranged together, one of the parts being partially cut away to constitute a slot on one side of the longitudinal center of the main part receiving the axle shaft, the inner end of the slot being adapted to 50 constitute a journal bearing to operate upon the shaft, said back part having a relatively thick and heavy portion opposite to the rearward side of said slot, a bolt connected to said parts adjacent to said bearing and securing the parts together, and a bolt connected to the back part and the main part and extending across said slot adjacent to the normally lower ends of said parts.

55 In testimony whereof I affix my signature 60 on this 24th day of September, 1926.

SAMUEL HUMMERSON.
